UNITED STATES PATENT OFFICE

ABRAHAM STEINSCHNEIDER, OF BERLIN, GERMANY

CASE FOR BOOKS OR THE LIKE

Application filed July 27, 1929, Serial No. 381,481, and in Germany August 16, 1928.

My invention refers to a case or a cabinet for storing books or other articles on superposed shelves, and more especially to the kind of case in which an endless row of superposed shelves is supported by a pair of endless chains and can be raised or lowered by moving the chains, so that each shelf can be moved in range of the eyes or hands of a person standing in front of the case.

In order that the shelves can be arranged in superposition without any appreciable clearance between them, they are as a rule not suspended directly on the chain links, but there are provided on the chains arms projecting at right angles to the chains, pins being secured to the free ends of these arms to support the shelves. In this construction each shelf, when passing over the sprockets carrying the chains, will be spaced from the shelf next following about the length of the arms carrying it, as otherwise a collision between adjoining shelves could not be avoided.

This construction involves the drawback, that the shelves being suspended at the outer ends of the arms, instead of at the chain direct, will load the chain outside of the plane in which the chain is moving, and the chain will therefore be distorted, the shelf acting on the outer ends of the arms, which are thus acting as levers. In consequence thereof the chains, when the shelves are loaded with books or the like, will be placed under a tension which will prevent their being moved altogether.

According to the present invention I succeed in avoiding this drawback by slotting the arms in horizontal direction and providing means for guiding the shelves in these slots in such manner, that on the vertically ascending and descending portions of the chain the pins fixed to the shelves and projecting into the slots bear against the inner ends thereof so that the shelves are suspended in the plane of travelling of the chain, whereby all lateral strains on the chain are avoided. I further provide means for avoiding collision between superposed shelves when passing around the sprockets, the pins fixed to the shelves being shifted by suitable guiding means adjoining the sprockets towards the

outer ends of the slots in the supporting arms, so that in the top and bottom positions the shelf passing around the sprockets will be spaced sufficiently from the shelf next following.

In the drawings affixed to this specification and forming part thereof, two modifications of a mechanism embodying my invention are illustrated diagrammatically by way of example.

In the drawings

Fig. 1 is a vertical section of an endless row of shelves with one of the chains supporting them,

Fig. 2 is a similar view of the top part of the chain and sprocket wheel carrying same illustrating the way in which the shelves are being guided when passing over the sprocket,

Fig. 3 illustrates a modified form of guiding means for the shelves passing over the sprocket, and

Figs. 4 and 5 are front elevations, partly in axial section, of a sprocket and a guide disc cooperating therewith.

Referring first to Figs. 1 and 2, 1 is the shaft carrying the upper sprocket wheels 2 and 3 is an endless chain supported on this sprocket wheel. 21 is the shaft of the lower sprocket wheel 2. 4 are slotted arms fixed at intervals to the chain and extending at right angles thereto, and 5 are the horizontal slots provided in these arms. 6 are the pins fixed to the middle of the top portion of the shelves and projecting freely into the slots and 7 are the shelves themselves, which are thus suspended from the arms 4 by means of the pins 6, which are so arranged, that when ascending or descending the shelves are held in their normal position. A guide disc 8 is associated with each sprocket 2, the diameter of these guide discs being greater than the diameter of the sprockets, and therefore the pins 6 fixed to the shelves, when meeting these discs, will be shifted outwardly in contact with the circumferential edges of the discs and towards the outer ends of the slots in which they are loosely supported. In consequence of this shifting movement the ascending shelf which is in course of being moved around the sprockets, will be spaced

from the shelf next following about a distance equalling the length of the slots 5, whereby collision of adjoining shelves is avoided. While being shifted in the slots, the pins 6 are guided outwardly by curved guide rails 10 provided at the top and bottom ends of the straight guide rails 9 which hold the pins in contact with the ascending or descending branches of the chain. After having passed around the sprockets the pins with the shelves will be shifted again inwardly towards the inner ends of the arms and into the plane of travelling of the vertical branch of the chain by the curved guide rails 10 provided for this purpose.

In order that the shelf bottoms be maintained in horizontal position, while the shelves are starting on the way around the sprockets, I provide separate pins 11 near the outer bottom corner of the side walls of each shelf. As shown in Fig. 3 a separate curved rail 12 is provided near the top end of the ascending branch of each chain, this curved guide rail 12 catching the pin 11 of the shelf which is about to be carried around the sprocket and the pin 11 will thus be guided by the rail 12 and the shelf will be prevented from assuming an oblique position. Obviously the rail 12 must end at the point where the pins 6 are leaving the ascending branch of the chain to be shifted outwardly by the discs 8. In order to further guide the pins 11 and the shelves on their way downwardly, after the shelf has passed around the sprockets, I provide a further curved rail 13 between the two branches of each chain. However, as this guide rail 13 acts on the pins 11 only from above, a toothed chain 16 supported on a disc 14 and a sprocket wheel 15 and guided by a curved guide way 18 is provided, the teeth 17 of this chain catching below the pin 11 and providing for its positive guidance in contact with the downwardly directed guide rail 13.

In order to prevent the pin 11 from slipping through the gap between the guide rails 12 and 13, I further provide on each side wall of the shelf a third pin 19 which is arranged slightly above and sideways of the pin 11, this pin 19, after having passed through the gap between the guide rails 12 and 13, being guided by a switch or short rail 20 which guides the pin 19, when the pin 11 is about to pass from the rail 12 over the rail 13. While pin 11 is travelling past the gap between the two rails, pin 19 is depressed by the rail 20, whereby pin 11 is prevented from slipping through the gap.

I wish it to be understood that I do not desire to be limited to the exact details of construction shown and described for obvious modifications will occur to a person skilled in the art.

In the claims affixed to this specification no selection of any particular modification of

the invention is intended to the exclusion of other modifications thereof and the right to subsequently make claim to any modification not covered by these claims is expressly reserved.

I claim:

1. Case for books or the like comprising a row of superposed shelves, an endless chain extending vertically at either end of said row of shelves, a top and a bottom sprocket wheel for supporting and guiding each chain, slotted arms fixed to and extending at right angles to said chains and a pin at each end of each shelf projecting into the slot of an arm.

2. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm and means near the vertical branch of each chain for keeping said pins near the inner ends of said slots.

3. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm, means near the vertical branch of each chain for keeping said pins near the inner ends of said slots and means near said wheels for shifting said pins towards the outer ends of said slots.

4. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm and guide rails near the vertical branch of each chain for keeping said pins near the inner ends of said slots.

5. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm, straight guide rails near the vertical branch of each chain for keeping said pins near the inner ends of said slots and discs near said wheels for shifting said pins towards the outer ends of said slots.

6. Case for books or the like comprising a row of superposed shelves, an endless chain extending vertically at either end of said row

of shelves, a top and a bottom sprocket wheel for supporting and guiding each chain, slotted arms fixed to and extending at right angles to said chains, a pin at each end of each shelf projecting into the slot of an arm, means near the vertical branch of each chain for keeping said pins near the inner ends of said slots and means near said wheels for shifting said pins towards the outer ends of said slots and back again.

7. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm, straight guide rails near the vertical branch of each chain for keeping said pins near the inner ends of said slots, discs near said wheels for shifting said pins towards the outer ends of said slots and curved rails for shifting said pins back again towards the inner ends of said slots.

8. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm, means near the vertical branch of each chain for keeping said pins near the inner ends of said slots, means near said wheels for shifting said pins towards the outer ends of said slots and means for maintaining said shelves in their normal position, while they are being shifted horizontally together with their pins.

9. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm, straight guide rails near the vertical branch of each chain for keeping said pins near the inner ends of said slots, discs near said wheels for shifting said pins towards the outer end of said slot, a second pin at each end of each shelf and curved rails for guiding said second pins so as to maintain said shelves in their normal position while they are being shifted horizontally together with their pins.

10. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm,

straight guide rails near the vertical branch of each chain for keeping said pins near the inner ends of said slots, discs near said wheels for shifting said pins towards the outer ends of said slots, a second pin at each end of each shelf and curved rails and endless toothed chains for guiding said second pins so as to maintain said shelves in their normal position while they are being shifted horizontally together with their pins.

11. Case for books or the like comprising a row of superposed shelves, an endless chain extending vertically at either end of said row of shelves, a top and a bottom sprocket wheel for supporting and guiding each chain, slotted arms fixed to and extending at right angles to said chains, a pin at each end of each shelf projecting into the slot of an arm, straight guide rails near the vertical branch of each chain for keeping said pins near the inner ends of said slots, discs near said wheels for shifting said pins towards the outer ends of said slots, a second pin at each end of each shelf and curved rails and endless toothed chains for guiding said second pins so as to maintain said shelves in their normal position while they are being shifted horizontally together with their pins, a third pin at each end of a shelf and switches for guiding said third pins so as to bring said second pins into engagement with said toothed chains.

In testimony whereof I affix my signature.
ABRAHAM STEINSCHNEIDER.
